[57] CLAIM

The ornamental design for a baby carrier, as shown and described.

DESCRIPTION

FIG. 1 is a front elevational view of a baby carrier in a folded condition showing our new design with the broken lines representing conventional stitching;

FIG. 2 is a rear elevational view thereof with the broken lines representing conventional stitching;

FIG. 3 is a side elevational view of the left side thereof;

FIG. 4 is a side elevational view of the right side thereof;

FIG. 5 is a top plan view thereof;

FIG. 6 is a bottom plan view thereof;

FIG. 7 is a perspective view from the front and left sides of the baby carrier in an expanded condition for actual usage on the front of a person wearing the carrier; and,

FIG. 8 is a perspective view from the front and right sides of the baby carrier as shown in FIG. 7 with the broken lines representing conventional stitching.
